UNITED STATES PATENT OFFICE.

THOMAS OGLE, OF BRAMLEY, NEAR LEEDS, ENGLAND.

MACHINE FOR DRYING HANKS OR WARPS OF YARN, WOVEN OR FELTED FABRICS, LEATHER, AND FIBROUS MATERIALS.

1,312,348.

Specification of Letters Patent. Patented Aug. 5, 1919.

Application filed October 5, 1918. Serial No. 256,949.

To all whom it may concern:

Be it known that I, THOMAS OGLE, subject of the King of Great Britain, residing at "Nunroyd," Stanningley Road, Bramley, near Leeds, in the county of York, England, have invented certain new and useful Improvements in Machines for Drying Hanks or Warps of Yarn, Woven or Felted Fabrics, Leather, and Fibrous Materials, and 10 of which the following is a specification.

This invention relates to machines for drying hanks or warps of yarn, woven or felted fabrics, leather and fibrous materials, of the kind wherein the moist goods are 15 automatically conducted through a longitudinal drying chamber by means of traveling chains, and in which air is circulated among the goods during their passage through the drying chamber by means of 20 fans contained within side compartments contiguous to the said drying chamber and which also contain heaters for warming the air thus circulated.

Hitherto in these machines, the air has 25 been made to circulate in the drying chamber either in an upwardly or downwardly direction or both, necessitating in some instances the drying chamber to be constructed with a perforated floor and ceiling communicating with air spaces above and below the said drying chamber leading into the side compartments containing the circulating fans and heaters.

This vertical circulation of the air however 30 is not entirely satisfactory in practice, particularly in the case where the goods to be dried are in the form of hanks, owing to the fact that the air by its upward or downward travel is only brought into contact with the exterior surfaces of the goods; 35 and the object of this present invention is to so improve the construction of these machines as to cause the heated air to be brought into much more intimate contact 40 with the goods during their passage through the drying chamber than that obtaining in previous constructions, thus greatly facilitating the drying operation.

According to my invention, the two side 45 walls or partitions of the longitudinal drying chamber are each formed with vertical or other slots or openings constituting passage ways between the said drying chamber and its two contiguous side compartments 55 containing the circulating fans and heaters,

the said slots or openings being arranged in groups comprising top and bottom sets alternately. The bottom sets of openings extend from the floor upward through which the moist air is drawn from the drying chamber by the fan or fans while the top sets of openings extend from the ceiling downward through which the same air after passing over the heaters is blown by the fan or fans into the drying chamber, or 60 vice versa; and the bottom sets of openings in one side wall or partition are situated directly opposite the top sets of openings in the other side wall or partition, so that, on the fan or fans being set in motion, the air 65 is caused to circulate across the drying chamber in a diagonal direction, either upward or downward or both.

By causing the air to be circulated diagonally across the drying chamber, the said 70 air is brought into much more intimate contact with the goods than heretofore; while in the case where the goods to be dried are in the form of hanks, this diagonal travel has the effect of causing the air to impinge 75 on the interior surfaces of the said hanks equally with that on their exterior surfaces, thus greatly facilitating the drying operation.

In order that my invention may be clearly 80 understood, I will proceed to describe the same with reference to the example of construction shown in the accompanying drawings; wherein:

Figure 1 is a longitudinal sectional side 85 elevation taken on line A—B, Fig. 2.

Fig. 2 is a sectional plan taken on line 90 C—D, Fig. 1, and Fig. 3 is a transverse sectional elevation taken on line E—F, Fig. 1.

Referring to the drawings, the machine 95 consists of a longitudinal drying chamber 1 which is open at one end 2 for the admission of fresh air and having its other end 3 closed and fitted with an exhaust fan 4, the said 100 drying chamber being further provided with endless traveling chains 5 for carrying the hanks 6 (Fig. 3) and having contiguous side compartments 7 fitted with fans 8 and heating surfaces 9; all of which are more or less 105 of known construction.

According to my invention, the side walls 110 or partitions 10, 11 of the longitudinal drying chamber 1 are each formed with a series of vertical slots or openings comprising top

and bottom sets 12, 13 and arranged alternately and which constitute passage ways between the said drying chamber 1 and the side compartments 7 containing the fans 8 and heaters 9. The bottom sets of openings 13 extend from the floor 14 upward while the top sets of openings 12 extend from the ceiling 15 downward, and the bottom sets of openings 13 in the said wall or partition 10 are situated directly opposite the top sets of openings 12 in the other side wall or partition 11; so that, on the fans 8 being set in motion, the moist air is drawn from the drying chamber 1 by way of the top sets of 15 openings 12 into the side compartments 7 through the medium of the fans 8, while the same air after passing over the heaters 9 is blown by the fans 8 into the drying chamber 1 by way of the bottom sets of openings 13 20 as indicated by arrows at Fig. 2, thus obtaining alternate right and left hand upward currents of air across the drying chamber 1 in the manner indicated by arrows at Fig. 3. In this way, the circulated air is caused to pass diagonally through interior 25 of the hanks 6 as well as diagonally across their exterior surfaces, whereby the drying operation is greatly facilitated.

In the operation of the hereinbefore described apparatus, the rods indicated at *a* 30 carry the wet hanks 6 shown in Fig. 3. These hanks 6 are passed into a magazine *c* as indicated in Fig. 1, where they are picked up one at a time by a roller *d* and transferred thereby on to a lower rail *e*. The wet hanks are carried along this lower rail *e* by the endless traveling chains 5 in the direction indicated by the arrows to the opposite end of the apparatus where they are lifted 35 by an auxiliary endless chain *f* and passed on to an upper rail *g* along which they are then carried by the endless traveling chains 5 in the direction shown by the arrows and thus returned to the front end of the machine where they are removed at *h* in the dried condition.

What I claim as my invention and desire to secure by Letters Patent is:—

1. In a machine for drying hanks or warps 50 of yarn, woven or felted fabrics, leather and fibrous materials, the combination of a longitudinal drying chamber fitted with traveling chains for conducting the moist goods through said drying chamber, side compartments contiguous to said drying chamber, fans for circulating air among the goods during their passage through said drying chamber, and heaters for warming the air circulated by said fans, there being slots or 55 openings so located in the side walls or par-

titions of said drying chamber leading into said side compartments as to cause the air set in motion by said fans to circulate across said drying chamber in a diagonal direction, either upward or downward or both. 6

2. In a machine for drying hanks or warps of yarn, woven or felted fabrics, leather and fibrous materials, the combination of a longitudinal drying chamber fitted with traveling chains for conducting the moist goods through said drying chamber, side compartments contiguous to said drying chamber, fans in said side compartments for circulating air among the goods during their passage through said drying chamber, and heaters within said side compartments for warming the air circulated by said fans, there being slots or openings in the side walls or partitions of the drying chamber leading into said side compartments arranged in groups comprising top and bottom sets alternately with the top sets of openings in one side wall or partition situated directly opposite the bottom sets of openings in the other side wall or partition so as to cause the air set in motion by said fans to circulate across said drying chamber in opposite directions. 80

3. In a machine for drying hanks or warps of yarn, woven or felted fabrics, leather and fibrous materials, the combination of a longitudinal drying chamber fitted with traveling chains for conducting the moist goods through said drying chamber, side compartments contiguous to said drying chamber, fans in said side compartments for circulating air among the goods during their passage through said drying chamber, and heaters within said side compartments for warming the air circulated by said fans, 90 there being slots or openings in the side walls or partitions of the drying chamber leading into said side compartments arranged in groups comprising top and bottom sets alternately and respectively extending from the ceiling downward and from the floor upward with the top sets of openings in one side wall or partition situated directly opposite the bottom sets of openings in the other side wall or partition so as to cause the air set in motion by said fans to circulate across said drying chamber in opposite directions. 95

In witness whereof I have hereunto set my hand in the presence of two witnesses.

THOMAS OGLE.
